UNITED STATES PATENT OFFICE

2,511,205

GAS BURNER FLASH TUBE

Philip S. Harper, Charles C. Lamar, and Vincent C. Peterson, Chicago, Ill., assignors of one-fourth to Philip S. Harper, and one-fourth to Carolyn L. Harper, both of Chicago, Ill., and one-fourth to Harris Trust and Savings Bank, an Illinois banking corporation, as trustee of The Philip S. Harper Trust, and one-fourth to said Harris Trust and Savings Bank as trustee of the Carolyn L. Harper Trust

Application April 30, 1945, Serial No. 591,128

3 Claims. (Cl. 158—115)

1

The present invention relates to gas burners and more particularly to flash tube assemblies for such burners.

Among the objects of the present invention is to provide a novel arrangement for a flash tube whereby the same is securely held in assembled relation with a lighter cup at one end thereof and a lighter jet at the other end thereof and which is associated with the gas burner in such a way that proper alignment of the various parts is obtained.

Another object of the present invention is to provide a novel flash tube assembly which is readily detachably connected with respect to the burner and which will be well secured in good alignment with the burner when the same is to be operated.

Still a further object of the present invention is to provide a novel flash tube system in which the flash tube is securely held in proper alignment with the pilot light at one end and with the lighter jet at the other end and with which lighter jet is associated socket means whereby the flash tube may be readily removed by lifting the tube at the pilot end and withdrawing the tube axially from the socket connection at the burner end.

Another object of the present invention is to provide a self-aligning flash tube system in which the flash tube may be readily disconnected from the burners to permit removal of the burners from the stove for cleaning purposes.

Another object within the purview of the present invention is to provide novel means for assembling a flash tube with a lighter jet at one end and a lighter cup at the other end, such means being constituted by a socket connection at the burner end and an interlocking relation of the flash tube with the lighter cup by gravity at the other end thereof.

Still a further object of the present invention is to provide a novel flash tube connection between a lighter cup and a lighter jet wherein the flash tube has perfect alignment at both burner and lighter ends and provides a fixed control of secondary air to the lighter port.

A further object of the present invention is to provide a readily removable flash tube which has perfect alignment at both burner and lighter ends and is adapted to carry ignition under a main burner section to a simmer burner.

Still another object of the present invention is to provide a novel mounting for a flash tube at the burner end involving the use of a socket connection having means for directing the flash from

2

the lighter jet over a substantial distance to the burner with which the lighter jet is associated.

A still further object of the present invention is to provide a novel flash tube connection between a lighter cup and a lighter jet wherein the flash tube has perfect alignment at both burner and lighter ends and adjustability with respect to said burner and lighter cup to accommodate variations in the distance therebetween, yet providing for a fixed intake for secondary air to the lighter jet under all conditions of adjustability.

Other objects, features, capabilities and advantages are comprehended by the invention, as will later appear and as are inherently possessed thereby.

Referring to the drawings:

Figure 1 is a top plan view of a gas burner incorporating a novel flash tube construction made in accordance with the present invention;

Figure 2 is a view in cross section taken in the plane represented by line 2—2 of Figure 1 of the drawings;

Figure 3 is a fragmentary view partly in section and partly in elevation taken in the plane represented by the lines 3—3 of Figure 2 of the drawings;

Figure 4 is a fragmentary view partly in section and partly in elevation of a modified form of connection between a flash tube and a burner;

Figure 5 is a fragmentary view in section taken in the plane represented by line 5—5 of Figure 4 of the drawings;

Figure 6 is a fragmentary view partly in elevation and partly in section of still another form of assembly for a flash tube with a burner and a lighter cup; and

Figure 7 is a fragmentary view partly in elevation and partly in section of a further form of assembly for a flash tube with a burner and a lighter cup.

Referring now more in detail to the drawings and particularly Figures 1—3, inclusive, a flash tube system selected to illustrate the present invention is disclosed in connection with a gas burner assembly which may contain a plurality of burners 2 with associated gas feeding means (not disclosed). Such a burner is shown in the drawings as comprising a simmer burner housing 4 and a main burner housing 6 of substantially annular shape surrounding the simmer housing 4 in spaced relation thereto. The main burner housing 6 is integrally formed with a lateral extension 8 adapted to be mounted as disclosed

upon a mixer tube casting 10, the said casting 10 being formed with the ducts 12 and 14.

The simmer burner housing 4 is provided with a chamber 16 communicating with the duct 14 wherein gas and air is mixed for supplying a combustible mixture to the simmer burner head 18 mounted in the upper end of the housing 4 and which is provided with the burner ports 20 in the wall thereof.

The main burner 6 is provided with a base portion 22 and a head 24 secured thereto to provide a chamber 26 communicating by way of a passage extending through the lateral extension 8 with the duct 12 whereby an air-gas mixture introduced into the duct is delivered through the chamber 26 to the burner ports 28 formed in the head 24. The double burner as disclosed is adapted to be operated with the simmer burner alone and with the simmer and main burners together. The control valve (not shown), when turned from the "off" position, first opens a passageway causing gas to flow to the simmer burner and then, when turned to the full "on" position, passes gas to both burners simultaneously. Since the simmer burner receives the combustible mixture first and may be operated independently, it is desired to ignite gas being emitted therefrom first.

The present invention is more particularly directed to novel means for mounting each of the flash tubes 30 of the burner assembly in proper alignment at one end with a lighter cup 32 associated with a pilot light 34 and with a lighter jet 36 at the other end. The lighter jet 36 is screw-threaded into the wall of chamber 4 and is formed with an enlarged head 38 adapted to secure a flash tube supporting member 40 in associated relation with the housing 4. The lighter jet as disclosed is provided with an opening 42 extending axially thereof and which is adapted to direct the combustible air-gas mixture from chamber 16 in an axial direction with respect to the flash tube 30.

Member 40 is formed with a socket 44 adapted to support the burner end of the flash tube 30 and is further provided with the upwardly and inwardly extending walls 46 and 48 providing an upwardly directed passageway 50 between the simmer burner housing 4 and the main burner housing 6, thereby directing the flash from the lighter jet 36 upwardly for igniting the air-gas mixture emitted from the burner ports 20. The flash tube 30 at its burner end terminates adjacent the fixed opening 56 provided in the member 40 whereby secondary air is admitted to support combustion at the lighter jet and in passageway 50.

The opposite end of the flash tube 30 is adapted to be supported within a recess 60 formed in the upper margin of the lighter cup 32 and said end of the flash tube is formed with an opening 62 adapted to receive a projection 64 extending upwardly at the central portion of the recess 60.

According to the disclosure of Figures 1-3, inclusive, the flash tube 30 is maintained in alignment both with the pilot light and the lighter jet and can be readily and easily assembled and disassembled with respect to the burner and the lighter cup. In the assembly of this flash tube, the same may be introduced into the socket member 40 and dropped by gravity into a position for locking engagement with the projection 64. The member 40 serves to support the burner end of the flash tube in underlying relation to the main burner 6 and also provides novel means for propagating flame from the lighter jet to the ports 20 of the simmer burner. The main burner ports

28 are ignited by the provision of the radially disposed slot 66 extending into flame propagating relation with said ports as well as the ports 20 of the simmer burner whereby cross lighting can be effected between the simmer and main burners.

Figures 4 and 5 illustrate a modified form of connection between the lighter jet and the flash tube. In this illustration, the burner assembly is shown as conforming to that disclosed in Figures 1-3 wherein the simmer burner housing 4 is provided with the chamber 16 communicating with the ports 20 of the burner 18 mounted in the upper end of said housing 4. The flash directing member 40 is of somewhat similar construction to that shown in Figure 2 except that no socket or bottom wall is provided. However, the same is mounted in association with the housing 4 through the medium of a lighter jet 68 varying in construction somewhat from the lighter jet 36 of the previously disclosed embodiment. In this form of construction, the lighter jet is provided with oppositely disposed lugs 70 and 72 adapted to be received through the openings 74 and 76 formed in the end wall 78 of the flash tube 80. Interlocking engagement between the flash tube 80 and the lighter jet 68 is effected by rotating the flash tube 80 into a position such that lugs 70 and 72 are received by the openings 74 and 76 after which the flash tube is rotated substantially 90 degrees to a position where lugs 70 and 72 are disposed to engage the end wall 78 of the flash tube for holding the same in proper associated relation with the lighter jet 68. The lugs 70 and 72 are so disposed as to permit a limited amount of axial movement of the flash tube 80 with respect to the lighter jet 68. Secondary air to support combustion in the vicinity of the lighter jet 68 is supplied through oppositely disposed fixed openings 77 and 79 formed in the end of the flash tube 80. The flash tube 80 may be held in proper relation to a lighter cup, such as 32, in the manner disclosed in the embodiment of Figures 1-3 of the drawings or, if desired, the flash tube may be formed as illustrated in Figure 6, as will be described hereinafter.

As will be clearly appreciated, since the burner end of the flash tube 80 is mounted upon the lighter jet 68, member 40 serves merely to direct the flash from lighter jet 68 upwardly to the ports 20 and does not function to support the flash tube 80. Accordingly, the mounting for the burner end of the flash tube disclosed in this figure may be effectively used with other types of burners where the burner ports may be disposed a shorter distance from the lighter jet than shown.

In Figure 6 is disclosed still another modified form of mounting for a flash tube in a burner assembly, the same being adapted for use in connection with a burner of the type more particularly shown in Figures 1 and 2 of the drawings. In this illustration, the flash tube 82 is mounted in operative position at one end on a lighter cup 84 and at the other end upon a channel member 86 connected in association with a simmer burner housing 4 provided with a chamber 16 as illustrated in the previously described embodiments and which chamber is adapted to deliver a combustible air-gas mixture to the ports 20 of a simmer burner 18.

The channel member 86 is provided with a central web 88 disposed adjacent the housing 4 and an outwardly extending central web 90, the said web 88 being apertured to fit over a lighter jet 92 mounted in the housing 4 and having an

enlarged head 94 adapted to secure the channel member 86 in proper position. The lighter jet 92 is formed with an axial opening 98 for projecting an air-gas mixture axially with respect to the flash tube 82. Adjacent the lighter jet 92 and formed in the central web 90 is a fixed opening 94 constituting an intake for secondary air to support combustion in the environment of the lighter jet 92. The flash tube 82 is mounted upon the central web 90 and is held against lateral displacement by the side walls such as 98 of the channel member. The other end of the flash tube 82 is formed with a restriction 100 to provide an annular recess fitting within the recess 102 of the lighter cup whereby lateral displacement of the flash tube 82 is prevented at and adjacent the lighter cup and the interlocking relation of the cup with the annular recess formed by the restriction 100 holds the flash tube against axial movement. In this modification, the upward displacement of flash tube 82 is prevented by the base 22 of the main burner housing 6. As will be apparent, the side walls 98, together with the main burner housing, provide a passageway for directing flames upwardly from the lighter jet 92 to the simmer ports 20 over a substantial distance for operating the simmer burner when desired. As in the previous illustrations, cross lighting between the simmer burner and main burner can be effected in the manner hereinbefore described.

In Figure 7 a further modified form of assembly for a flash tube with a burner and lighter cup is disclosed. In this embodiment the burner may include the housing 4 conforming to that hereinafore disclosed in the previously described forms of the invention and which has threadedly mounted therein a lighter jet 36 adapted to serve as securing means for member 40 constructed as shown in Figure 4 of the drawings. In this form of construction, the flash tube 104 is provided with an apertured end wall 105 fitting over the enlarged head 38 of the lighter jet whereby the burner end of the flash tube 104 is supported in alignment with the lighter jet 36. The flash tube is further provided with the oppositely disposed fixed openings 108 and 110 in the side walls thereof for the purpose of supplying secondary air to support combustion in the vicinity of the lighter jet 36. The other end of the flash tube 104 may be supported by and interlocked with a lighter cup in the manner hereinbefore disclosed in Figures 2 and 6. This form of construction has all of the advantages hereinbefore set forth and described in connection with the disclosure of the previous embodiments of the invention.

For the reasons hereinbefore set forth in connection with the description of the embodiment of Figure 4, the member 40 may be dispensed with under the conditions indicated.

It should be noted that in each of the several embodiments of the invention, provision is made for a fixed intake for secondary air to the lighter jet, yet providing for an adjustment of the flash tube with respect to the burner which may be necessary because of variations in the distance between the burner and the pilot light. It should be further noted that, in accordance with the present invention, provision is made for fixed area secondary openings which in certain of the embodiments are independent of the position of the end of the flash tube and which in certain other of the embodiments are in fixed relation to the lighter jet, and independent of the position of the end of the flash tube. From the above descrip-

tion, it will be noted that the channel member serves as a mounting for the end of the flash tube and as a means for maintaining the same in proper relationship to the lighter jet and to the side wall of the gas chamber. Novelty is found in the utilization of a horizontally projecting gas jet as a locating means for the channel member in association with other means for anchoring or holding the channel so located on the jet. One holding means is shown in Figure 2 of the drawing, wherein the jet is equipped with a head which accomplishes the holding function. When the jet has an integrally formed head thereon, as shown in Figure 2 of the drawing, the shank of the jet constitutes the locating means and the head thereof constitutes the anchoring or holding means. Instead of making the head and jet as integral parts, these two means could be formed separately, in which case the head could be fastened to the jet in any suitable manner. When the jet is made without a head, other suitable holding means can be employed for holding the channel in its located position.

While we have herein described and upon the drawings shown an illustrative embodiment of the invention, it is to be understood that the invention is not limited thereto but may comprehend other constructions, arrangements of parts, details and features without departing from the spirit of the invention.

What is claimed is:

1. In a gas burner assembly, the combination of a double burner formed with an inner housing and an outer annular housing spaced therefrom, said housings having chambers for receiving a combustible air-gas mixture and being provided with burner ports, said inner housing having a lighter jet in spaced relation to said inner burner ports, a member located exteriorly on said inner housing in enclosing relation with said lighter jet and providing spaced substantially vertically disposed walls connected by an intermediate web, said walls defining a passageway between said housings for directing the flash at the light jet in the direction of said inner burner ports, said walls and web being formed to provide a socket at the end of said member spaced from the inner housing and which is disposed below the bottom of said outer housing, a lighter cup spaced from said inner housing, and a flash tube releasably mounted at one end in said socket and having releasable securing at its other end with said lighter cup.

2. A device of the character described, adapted for use with a cooking stove gas burner having a gas chamber provided with a substantially vertically disposed side wall and adapted for holding one end of a flash tube in igniting relationship to said gas burner, said device comprising a channel member having a base, two spaced side walls and an end wall, said end wall having an opening therethrough, a stud-like member adapted to extend through and project horizontally from the substantially vertical side wall of said gas chamber, said stud-like member extending through and having locating association with said opening in the end wall of said channel member, said stud having a gas-feeding orifice therethrough adapted, when installed, to extend into said gas chamber and to constitute a lighter jet, said channel member being constructed to receive and to hold a flash tube with its axis disposed in substantial alignment with the axis of said lighter jet and with its end in spaced but gas-feeding relation to said lighter jet, and holding means engaging a portion of said channel mem-

ber and holding the same against accidental displacement when said channel member is properly located on and by said stud-like member.

3. A device of the character described, adapted for use with a cooking stove gas burner having a gas chamber provided with a substantially vertically disposed side wall and adapted for holding one end of a flash tube in igniting relationship to said gas burner, said device comprising a channel member having a base, two spaced side walls and an end wall, said end wall having an opening therethrough, a stud-like member adapted to extend through and project horizontally from the substantially vertical side wall of said gas chamber, said stud-like member extending through and having locating association with said opening in the end wall of said channel member, said stud having a gas-feeding orifice therethrough adapted, when installed, to extend into said gas chamber and to constitute a lighter jet, said channel member being constructed to receive and to hold a flash tube with its axis disposed in substantial alignment with the axis of said lighter jet and with its end in spaced but gas-feeding relation to said lighter jet, and holding means engaging a

10

portion of said channel member and holding the same against accidental displacement when said channel member is properly located on and by said stud-like member, said holding means consisting of a head on said stud-like member.
